HEADREST SOCKET FOR BARBER CHAIRS

Filed July 13, 1928

UNITED STATES PATENT OFFICE

JOHN R. EMMERT, OF CHICAGO, ILLINOIS, ASSIGNOR TO EMIL J. PAIDAR COMPANY, A CORPORATION OF ILLINOIS

HEADREST SOCKET FOR BARBER CHAIRS

Application filed July 13, 1928. Serial No. 292,529.

This invention relates to a barber chair and concerns itself with means for preventing the accumulation of hair in the back of the chair that may enter thru the head rest slot.

5 The invention comprises the novel structure and combination of parts hereinafter described and more particularly pointed out and defined in the appended claim.

In the accompanying drawings, which 10 illustrate a preferred embodiment of this invention and in which similar reference numerals refer to similar features in the different views:

Figure 1 is a perspective view of a barber 15 chair embodying this invention.

Figure 2 is an enlarged fragmentary sectional view upon the line II—II of Figure 1.

Figure 3 is an enlarged sectional view upon the line III—III of Figure 1.

20 Figure 4 is an enlarged view upon the line IV—IV of Figure 3.

Figure 5 is an enlarged sectional view taken upon the line V—V of Figure 3.

Figure 6 is an enlarged fragmentary sectional view taken upon the line VI—VI of 25 Figure 4.

Figure 7 is an enlarged sectional view taken upon the line VII—VII of Figure 4.

In the drawings, there is shown a common 30 form of barber chair, to which this invention has been applied. The barber chair embodies a head rest 1, which is provided with a shank 2, which slidably and adjustably fits in a slot or socket 3 in the top of the back 4 of the chair and in a groove 3^a formed in a wooden strip 5 that extends down to the lower frame member 7 of the back.

35 In cutting hair, the head rest is usually removed from the chair, with the result that 40 particles of hair will drop down thru the socket 3 and accumulate in the groove 3^a. In time there will be an accumulation of hair in the groove 3^a that will bulge the covering 4^a on the back of the chair. This accumulation 45 of hair is generally wet and, of course, injurious to the chair.

In order to overcome this objection, a hair 50 exit 6 communicating with the groove 3^a is provided in the bottom member 7 of the back

the groove 3^a may escape or be forced by a wire rod or the like, and, to expedite the downward movement of such hair, a metal channel-like member 8 or the like is inserted in said groove 3^a. This channel member has a 55 web 9 with side flanges 10 which are turned in, as indicated at 11. The shank of the head rest slidably fits in the channel and under the inturned flanges 11. This channel member provides an efficient guideway for the shank 60 and at the same time the hair finding its way therein will more readily gravitate to the bottom and escape thru the exit 6.

The flanges 10 of the channel member 8 are provided with incisions 12 (Fig. 4) a short 65 distance from the bottom thereof, and the flange portions below said incisions are stamped into arcuate form with the lower ends flattened against the web 9 to form sockets for retaining cushioning elements 13 for 70 the shank 2 when the same drops a sufficient distance in the groove 3^a.

It will be readily obvious that this invention eliminates any objectionable accumulations of hair in the guideway in the back of 75 the chair and provides an easy way for the removal thereof.

I am aware that many changes may be made and numerous details of construction 80 may be varied through a wide range without departing from the principles of this invention, and I, therefore, do not purpose limiting the patent granted hereon otherwise than necessitated by the prior art.

I claim as my invention:

In a barber chair, a metal guide having a 85 web with flanges, said flanges being formed at one end to provide sockets, and buffers seated in said sockets.

In testimony whereof I have hereunto subscribed my name at Chicago, Cook County, Illinois.

JOHN R. EMMERT.
